UNITED STATES PATENT OFFICE.

MARTIN D. MAY, OF MONROE, MICHIGAN.

CONCRETE FORM.

Application filed October 10, 1924. Serial No. 742,890.

To all whom it may concern:

Be it known that I, MARTIN D. MAY, a citizen of the United States, residing at Monroe, in the county of Monroe and State 5 of Michigan, have invented new and useful Improvements in Concrete Forms, of which the following is a specification.

This invention relates to a form for concrete, the general object of the invention being to provide means whereby concrete walls can be easily and quickly constructed of various widths and the parts of the form taken apart after the completion of the wall and reassembled for a new wall or part 15 thereof.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a section on line 1—1 of Figure 2.

Figure 2 is a section on line 2—2 of Figure 1.

Figure 3 is a perspective view of one of the corner pieces.

Figure 4 is a perspective view of portion 35 of one of the foot parts.

Figure 5 is a perspective view of one of the intermediate portions.

Figure 6 is a view similar to Figure 1 but showing a modification.

Figure 7 is a view of a part of the form shown in Figure 6.

Figure 8 is an elevation of a part of the form shown in Figure 6.

In these views, 1 indicates a plurality of 45 upright posts which are preferably formed of channel iron. These posts are provided with holes for receiving the bolts 2 which are threaded from end to end for receiving the lock nuts 3 and the spreader nuts 4. The

50 wall forming parts of the form consists of the pieces 5 and the upper pieces 6 and the corner pieces 7, these corner pieces being made similar to the pieces 5 and 6 but of angle construction in cross section so as to 55 form the corners of the building. Each foot piece has its lower part 8 offset from

the upper part 9 and the connecting piece 10 is slightly inclined, as shown. Thus the wall formed by these foot pieces will have a wide base with sloping shoulders which 60 connect the base with the major part of the wall. A flange 11 is formed at the bottom of the foot piece and an L-shaped flange 12 is formed at the top thereof. The pieces 6 are formed with L-shaped flanges 13 at 65 their upper and lower edges and the bottom flange 13 of the piece 6 is placed upon the flange 12 of the footing piece 5. Then another piece 6 is placed upon the first piece 6 until the form is of the desired height. The 70 pairs of pieces are connected together by the bolts 2 which pass through holes 14 formed in the pieces and the nuts 4 hold the pieces in their adjusted positions on the bolts. Thus the portions of the forms can be spaced any 75 desired distance to make a wall of the proper thickness. The L-shaped flanges of the various pieces are connected together by the usual clips 15. The corner pieces 7 are of angle construction as before explained and 80 the lower parts are provided with the enlarged base 7' and these corner pieces are provided with a plurality of rows of holes 14' for receiving the bolts and I arrange the holes in the pieces 5 and 6 in pairs which 85 are arranged closer together than the holes 14' in the corner pieces 7 so that a final adjustment can be made without weakening the corner pieces 7 by placing the holes therein closer together. The pieces 5 and 90 6 overlap the corner pieces, as shown in Figure 2, while the pieces 5 and 6 have their edges abutting each other and in order to prevent the concrete from escaping between these abutting edges I may provide sliding 95 pieces 16 to cover the joints as shown in Figure 2. These pieces may be made of the same cross sectional shape as the footing pieces 5 and the pieces 6 but slightly smaller so that they can slide in such pieces and thus 100 be adjusted to properly cover the joints. These sliding pieces can also be used to form extensions of the form where it is not desired to use the entire width of the pieces 5 and 6.

It will thus be seen that I have provided a wall form which can be easily and quickly erected and disassembled and the parts of which can be adjusted so as to make a wall of the desired thickness. The inside and outside adjustable corner pieces provide means whereby various combinations may be

worked out in erecting buildings. The forms can be inverted so as to make a wall coping.

Instead of using the pieces shown in Figure 5 I may use the pieces shown at 17 in Figures 6, 7 and 8 which are formed of the frames 18, to which metal plates 19 are secured. The frame rests upon the flanges of the footing pieces and the bolts 2' pass through holes formed in these frames so that it is not necessary to use the clips 15. In other respects this form of the invention is similar to that before described. Figure 8 shows how the parts are arranged so that they will break joints and thus increase the strength of the structure.

It is thought from the foregoing description that the advantages and novel features of my invention will be readily apparent.

I desire it to be understood that I may 20 make changes in the construction and in the combination and arrangement of the several parts, provided that such changes fall within the scope of the appended claims.

What I claim is:—

1. A form of the class described comprising uprights, sectional wall forming pieces having flanges thereon engaging the uprights, bolts passing through the uprights and said pieces, spreader nuts on the bolts engaging the pieces and lock nuts on the bolts engaging the uprights. 25

2. A form of the class described comprising uprights, sectional wall forming pieces including footing pieces and corner forming pieces, the corner forming pieces being of angle shape in cross section, bolts passing through the pieces and the uprights, spreader nuts on the bolts for engaging the bolts, lock nuts on the bolts engaging the uprights and the footing pieces and the corner pieces having offset portions at their lower ends for forming a wide base on the wall. 35

40 In testimony whereof I affix my signature.

MARTIN D. MAY.
